(57) **CLAIM**

We claim the ornamental design for a partition, as shown and described.

DESCRIPTION

FIG. 1 is a front perspective view of a partition, showing our new design;

FIG. 2 is a rear perspective view of the partition thereof;

FIG. 3 is a front view of the partition thereof;

FIG. 4 is a rear view of the partition thereof;

FIG. 5 is a right side view of the partition thereof, the left side view is a mirror image of the right side view of FIG. 5;

FIG. 6 is a top view of the partition thereof;

FIG. 7 is a bottom view of the partition thereof;

FIG. 8 is an enlarged front perspective view of the portion of the partition of FIG. 1 identified at line VIII thereof;

FIG. 9 is an enlarged rear perspective view of the portion of the partition of FIG. 1 identified at line VIII thereof;

FIG. 10 is an enlarged front view of the portion of the partition of FIG. 1 identified at line VIII thereof;

FIG. 11 is an enlarged rear view of the portion of the partition of FIG. 1 identified at line VIII thereof;

FIG. 12 is an enlarged right side view of the portion of the partition of FIG. 1 identified at line VIII, the enlarged left side view is a mirror image of the enlarged right side view of FIG. 12 thereof;

FIG. 13 is an enlarged top view of the portion of the partition of FIG. 1 identified at line VIII thereof;

FIG. 14 is an enlarged bottom view of the portion of the partition of FIG. 1 identified at line VIII thereof;

FIG. 15 is a front perspective view of a second embodiment of a partition, showing our new design;

FIG. 16 is a rear perspective view of the second embodiment of a partition thereof;

FIG. 17 is a front view of the second embodiment of a partition thereof;

FIG. 18 is a rear view of the second embodiment of a partition thereof;

FIG. 19 is a right side view of the second embodiment of a partition thereof, the left side view is a mirror image of the right side view of FIG. 19 thereof;

(Continued)

FIG. 20 is a top view of the second embodiment of a partition thereof;
 FIG. 21 is a bottom view of the second embodiment of a partition thereof;
 FIG. 22 is an enlarged front perspective view of a portion of the partition of FIG. 15 identified at line XXII thereof;
 FIG. 23 is an enlarged rear perspective view of the portion of the partition of FIG. 15 identified at line XXII thereof;
 FIG. 24 is an enlarged front view of the portion of the partition of FIG. 15 identified at line XXII thereof;
 FIG. 25 is an enlarged rear view of the portion of the partition of FIG. 15 identified at line XXII thereof;
 FIG. 26 is an enlarged right side view of the portion of the partition of FIG. 15 identified at line XXII, the enlarged left side view is a mirror image of the enlarged right side view of FIG. 26 thereof;
 FIG. 27 is an enlarged top view of the portion of the partition of FIG. 15 identified at line XXII thereof; and,
 FIG. 28 is an enlarged bottom view of the portion of the partition of FIG. 15 identified at line XXII thereof.
 The broken lines are for purposes of illustrating boundaries and form no part of the claimed ornamental design.
